UNITED STATES PATENT OFFICE.

MORITZ HONIGMANN, OF AIX-LA-CHAPELLE, GERMANY.

PRODUCTION OF STEAM AT A HIGH PRESSURE FROM STEAM AT A LOWER PRESSURE.

SPECIFICATION forming part of Letters Patent No. 333,223, dated December 29, 1885.

Application filed July 17, 1885. Serial No. 171,836. (No model.)

To all whom it may concern:

Be it known that I, MORITZ HONIGMANN, of Aix-la-Chapelle, Germany, have invented new and useful Improvements in the Production 5 of Steam at a High Pressure from Steam at a Much Lower Pressure; of which the following is a specification.

This invention relates to the production of steam at a high pressure from steam at a much 10 lower pressure. This is effected in the manner and by the agency of the means hereinafter described.

Reference is to be had to the accompanying drawing, which represents a vertical section 15 of an example of an apparatus suitable for the purpose.

A vessel, N, containing soda or potash lye or other solution having a high boiling-point and a vessel, W, provided with circulating-tubes S, are so arranged, the one within or in 20 relation to the other that heat can be quickly transferred from the one to the other, and the differences of temperature between the two liquids quickly equalized, the two vessels being 25 respectively constructed to sustain the primitive and increased pressures. Steam under pressure is conveyed by a perforated pipe, L', into the soda-lye, of which the temperature becomes in consequence quickly 30 raised. If, for instance, the boiling-point of the soda-lye (under atmospheric pressure) is 150° Celsius, and the temperature of the original steam is 160° Celsius (which corresponds to a pressure of five atmospheres) the temperature 35 of the soda-lye will, in consequence of the absorption of the steam, be raised to 160+50=210° Celsius, while the pressure in the soda-vessel N is raised to five atmospheres. The temperature in the water-vessel W is conse- 40 quently raised to about 210° Celsius, whereby steam will be generated and raised to a pressure of from fifteen to twenty atmospheres. Thenceforth for every quantity of steam under a pressure of five atmospheres which is 45 blown into the soda-lye an equal quantity of steam under a pressure of fifteen to twenty atmospheres may be obtained from the water-vessel. In consequence of the absorptions of steam the boiling-point of the soda-lye becomes 50 gradually lowered and pressure in the water-vessel becomes correspondingly decreased, and when the solution is so far diluted as to be no

longer available, the soda-lye can be reconcentrated by means of the steam under pressure. This is effected in the following way: 55 The valves V³ and V⁴ are closed, and V⁵ is opened to allow the pressure in the soda-vessel to escape to the atmosphere. Steam under a pressure of five atmospheres, or at a temperature of 160° Celsius, is then blown into the 60 water-vessel W, where it becomes absorbed, and the diluted soda-lye is evaporated as the temperatures become equalized. The concentration of the soda-lye continues until its boiling-point corresponds to the temperature 65 of the steam used, which, in the example, is 160° Celsius.

For constant work two similar apparatus are used, which alternately raise the steam-pressure and concentrate the lye. The increase 70 of steam-pressure which can be obtained with this apparatus will be seen from the following table:

TABLE.

Steam under pressure.		Raised pressure of the steam.	
Pressure in atmospheres.	Temperature in Celsius.	Pressure in atmospheres.	Temperature in Celsius.
2	135	5 to 6½	150 to 170
3	145	8 " 11	170 " 190
4	153.3	11 " 15	190 " 206
5	160	15 " 22	206 " 220
6	166.5	22 " 30	220 " 233
7	172.1	30 " 35	233 " 245
8	177.4	35 " 40	245 " 255
9	182	40 " 50	255 " 264
10	186	50 " 60	264 " 272

This apparatus can be used for various purposes. For steam-engines it allows of the use of smaller steam-pipes and smaller engines 90 with a greater expansion.

This apparatus resembles the soda-steam boiler, but while in the latter the exhaust from the engine is returned to the boiler, thereby constituting a fireless working of the engine, 95 the present invention only aims to produce steam at a high pressure from steam already under pressure.

It is to be observed that the working of this apparatus and the obtaining of the greatest 100 pressure of steam are without any danger, as the difference of the temperature between the soda and the water cannot exceed 4° Celsius. The boiler requires no cleaning, as the steam

which enters carries no lime with it. Soda and potash are the most suitable for the purposes of this process, as they have very high boiling-points and are cheap and durable. 5 Copper resists perfectly the highest concentration of the soda-lye, and this metal being a good conductor of heat is very suitable.

I claim—

1. The improvement in the art of generating steam, consisting in generating from water steam at a pressure above that of the atmosphere, causing such steam to pass directly to and be absorbed by an alkaline lye or other solution having a high boiling-point, and employing the heat produced by such absorption to generate from other water steam at a pressure higher than that absorbed, substantially as herein described. 15

2. The within-described improvement in the art of generating steam at high pressure by means of heat obtained by the absorption of steam of a lower pressure into solution of high boiling-point in a vessel separate from the vessel in which such generation is effected, 20 said improvement consisting in effecting the reconcentration of said solution by introduc-

ing into the steam-generating vessel steam of a pressure and temperature corresponding with that of the steam originally absorbed, substantially as herein described. 30

3. The within-described improvements in the art of generating steam at a high pressure by means of heat obtained by the absorption of steam of a lower pressure into an alkaline solution in a vessel separate from the vessel 35 in which such generation is effected, and afterward reconcentrating the solution by introducing steam into the generating-vessel, said improvement consisting in the employment of two similar sets of heat absorbing and generating vessels in such alternative manner that while steam is being generated in one set the concentration of the solution is being performed in the other one, substantially as herein described. 40

In testimony whereof I have signed my name to this specification in the presence of two subscribing witnesses.

MORITZ HONIGMANN.
